UNITED STATES PATENT OFFICE.

CARL BECKMANN, OF NEW YORK, N. Y.

GAS-ENGINE.

960,063.

Specification of Letters Patent. Patented May 31, 1910.

Application filed December 29, 1908. Serial No. 469,796.

To all whom it may concern:

Be it known that I, CARL BECKMANN, a citizen of the United States, and a resident of the city of New York, borough of Brooklyn, in the county of Kings and State of New York, have invented a new and Improved Gas-Engine, of which the following is a full, clear, and exact description.

This invention relates to gas engines, and particularly to explosion engines actuated by a liquid or gaseous fuel.

The object of the invention is to produce an engine of this class of very compact and serviceable form, having an extremely simple valve mechanism. In both forms of the invention the engine operates as a two-cycle engine.

The invention comprises a compact arrangement of cylinders about a central shaft, having inclined or skew wrist pins or cranks, and by means of the cranks the reciprocating movement of the pistons is transformed into a rotary movement at the shaft. The wheel is so constructed that it operates as a valve controlling the admission and exhaust of the cylinders.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a section taken through the engine substantially on the line 1—1 of Fig. 2, in this view the cylinders and other parts not shown in section are omitted so as to render the view more intelligible; Fig. 2 is a vertical section on the line 2—2 of Fig. 1; Fig. 3 is a vertical section on the line 3—3 of Fig. 1; Fig. 4 is a perspective showing a portion of the wheel and one of the explosion cylinders, this view illustrates particularly the igniting devices; Fig. 5 is a vertical section through an engine and showing a modified form of the invention, this section is taken through the modified form of engine at a plane corresponding to the plane 2—2 of Fig. 1; and Fig. 6 is a vertical section through the modified form of engine and taken in a plane corresponding to the plane 3—3 of Fig. 1.

Referring more particularly to the parts, and especially to Figs. 1 to 4, inclusive, 1

represents the engine casing, which is in the form of a circular shell composed of two dished sections 2 which are bolted together, as shown. The sections 2 are enlarged at their central portions so as to form hub housings 3 containing hub chambers 4, as shown. Through the housings 3 a shaft 5 passes loosely, as indicated, said shaft being in a horizontal position and being mounted in inboard bearings 6 on each side of the case. Beyond these bearings 6 the shaft is formed with cranks 7 which have inclined or skew wrists 8. The middle points of these wrists lie on the axis of the shaft, and the webs 9 of the cranks are disposed opposite to each other, as shown. Beyond the cranks 7 the shaft is formed with end extensions 10 which are in axial alignment with the body of the shaft and mounted in outboard bearings 11. On the wrists 8, a pair of rockers or spiders 12 are loosely attached, said spiders having arms 13 formed with balls 14 at their extremities, said balls enabling the connecting rods 15 to be attached by means of ball sockets 16, as indicated. The connecting rods 15 are pivotally attached by pins 17 to pistons 18. These pistons reciprocate in cylinders E', E², E³, and C', C², C³. These cylinders are bolted to the side faces of the case 1, as indicated in Fig. 1, so that the axes of the cylinders are parallel with the axis of the shaft 5. As shown in Fig. 2, these cylinders are disposed equidistant from each other. The cylinders E', E², E³ are explosion cylinders, while the cylinders C', C², C³ are compressor cylinders. The cylinders consist simply of cylindrical walls without heads, the walls of the case constituting the heads for the cylinders, as indicated in Fig. 1. In the operation of this engine it should be understood that the explosions take place in the cylinders E', E², E³, while the charges for these cylinders are compressed in the cylinders C', C², C³. No explosions take place in the compressor cylinders.

Rotatably mounted within the casing 1, there is provided a wheel 19, which wheel is attached to the shaft 5 and operates as a fly wheel as well as a valve controlling the admission to the different cylinders. The inner portion of this wheel is formed into a main chamber or receiver 20, and near the hub 21 of this wheel, openings 22 are provided which admit a gaseous fuel into this chamber from the chamber 4, referred to

above. The fuel is supplied to the chamber 4 through a suitable supply pipe 23, controlled by a valve 24, as indicated. The fly wheel consists substantially of two disks 25 which lie flat against the inner faces of the shells 2, the said disks being separated to form the chamber 20, as will be readily understood. The rim of the fly wheel is a continuous hollow rim presenting a circular inner wall 26 and a circular outer wall 27. The space between these walls 26 and 27 is divided by a web 28 into two annular compressing chambers 29. The sides of the wheel are provided with compressor inlet ports 30. These ports extend around on the wheel throughout substantially one-half the circumference, as indicated in Fig. 2. It should be understood that there is one of these ports in each side of the wheel, said 20 ports being disposed opposite to each other. At suitable points, the ports are provided with bridges or webs 31. In addition to these ports 30, the side faces of the wheel are provided with compressor delivery 25 ports 32. These ports are curved, as indicated, so that they are disposed along a circumference struck from the axis of the shaft as a center like the ports 30. In Fig. 2 the arrow indicates the direction of rotation of the wheel, and for this direction of rotation the compressor delivery ports should have the relative position shown in this figure, that is, they should be slightly in advance of the compressor inlets. These 30 ports 32 are slightly farther from the axis of the shaft than the ports 30. The compression cylinders C', C², C³, are provided with inlet ports 33, and outlet ports 34. These ports are simple rectangular openings formed in the wall of the case, as indicated. The ports 33 are in alinement with the compressor inlets 30, and the ports 34 are in alinement with the compressor delivery ports 32. It should be stated that the 40 compressor delivery ports 32 are formed in the outer walls of the compressing chambers 29 so that communication between the ports 30 and 32 within the wall 27 is cut off by the wall 26.

50 Referring now particularly to Fig. 2, the disks of the wheel are provided with explosion exhaust ports 35 which are of circumferential form, and these ports extend around through substantially one-half of the circumference, being arranged on the opposite side of the axis from the ports 30. In addition to these ports 35, explosion inlet ports 36 are provided. These ports are curved along an arc struck from the center 55 of the shaft, like the other ports, but these ports 36 are quite short and cover in angular degrees only about one-eighth of the entire circumference. As indicated in Fig. 2, these ports 36 are opposite to the forward end of the ports 30 with respect to the di-

rection of the rotation indicated by the arrow. In alinement with the ports 36 I provide in the outer face of the wheel, igniting pockets 37 which are arc-shaped, as indicated, and provided with igniting coils 38. 70 The explosion cylinders are provided with inlet ports 39 and with exhaust ports 40. The inlet ports 39 are in alinement with the ports 36, whereas the exhaust ports 40 are in alinement with the explosion exhaust 75 ports 35 of the wheel. In order to start the engine up the explosion cylinders E', E², E³, are provided with spark plugs 41 arranged as shown.

The mode of operation of this type of 80 engine will now be described.

The fuel being admitted to the pipe 23 flows into the receiving chamber 20 near the center of the wheel. As the wheel rotates and as the ports 30 arrive at the ports 33 85 they will admit the gas into the compressor cylinders. As indicated in Fig. 2, the port 30 has just arrived at the port 33 of the compressor cylinder C². The position of the piston of this cylinder at this time is indicated in Fig. 1 in the lower part thereof. The outward stroke of the piston has just begun and as it takes place it draws in a charge until the port 30 passes out of communication with the port 33. This takes 90 substantially one-half of the revolution of the wheel. On the in-stroke of the piston of this cylinder C², the charge within the cylinder is compressed and this compression continues until the compression delivery 100 port 32 comes into communication with the outlet port 34 from this cylinder. When this takes place within the cylinder the charge which is compressed is discharged into the adjacent compressing chamber 95 105 of the wheel. As the revolution of the wheel continues, the port 36 of the wheel comes into alinement with the port 39 of the cylinder E² and a compressed charge of gas passes into this cylinder. The forward 110 end of this port 36 is in alinement with the forward end of the port 30 and consequently when the port 36 arrives at the port 39 the piston of the cylinder E² will be just beginning its outward stroke. Admission of gas 115 into this cylinder continues until the port 36 passes out of communication with the port 39, at which time a cut off will occur. Immediately after cut-off occurs ignition 120 takes place by means of the igniting coil 38 120 which will come into alinement with the port 39, as indicated; an explosion then occurs in the cylinder E². When this explosion occurs the crank will be in about its quarter position, that is, it will have made one-quarter of a revolution from its dead center 125 position for this cylinder. In this way, as the wheel rotates each of the compressor cylinders receives and compresses a charge 130 for its corresponding explosion cylinder,

and the explosions in the cylinders take place in succession and in rotation. After the explosion has occurred, about three-eighths of a revolution will take place before 5 exhaust which begins as soon as the explosion exhaust port 35 comes into alinement with the port 40. This exhaust port covers substantially 180° so that on all of their inward strokes the explosion cylinders are 10 open to exhaust.

In Fig. 1 the explosion cylinder E³ is represented with its pistons on dead center, that is, the crank is in a position in which no turning effort could be exerted by a force 15 acting on the piston. At the time that the explosion would occur in this cylinder, however, the crank would be in its quarter position, as suggested above. On account of the manner in which the explosions occur it will 20 be evident that the shaft is rotated by a succession of rotative impulses imparted to the cranks in their quarter positions. It should be understood that the cylinder and port arrangements on both sides of the engine are 25 symmetrical. In order to balance the reciprocating parts, the cranks 7 are inclined in opposite directions instead of being parallel with each other. From this arrangement it follows that pistons on opposite sides of 30 the shell are moving simultaneously both toward the case or both away from the case. This reduces vibration.

The manner in which the igniting coil 38 comes into alinement with the ports 39 in 35 order to cause ignition, is fully illustrated in Fig. 4. The coil 38 is formed of some metal which will retain the heat imparted to it when the explosion occurs, and remains sufficiently heated to cause explosion of the 40 next charge, but attention is called to the ignition plugs 41 which may be used if desired, not only for starting the engine but for maintaining the ignition after the engine is running. These spark plugs may 45 then be used in connection with a timer of any suitable construction.

In the modified form of the invention indicated in Figs. 5 and 6, a case 42 is provided which is similar to the case described in connection 50 with the preferred form. In this form of the invention I do not employ compressor cylinders, but I provide a plurality of explosion cylinders 43 which are arranged circumferentially and secured to the 55 sides of the case, as indicated in Fig. 5. The connections from the pistons of these cylinders to the cranks are the same as in the preferred form, and the construction of the crank is also the same. In this form of the 60 invention the cylinders are provided with inlet ports 44 and exhaust ports 45 which are arranged as shown. The wheel is formed as before, but the compressor chambers are omitted so that a receiving chamber 65 46 is formed within the wheel encircled by

a wall 47. Beyond the wall 47, flanges 48 are formed on the wheel, and in these flanges exhaust ports 49 are provided. These exhaust ports 49 are adapted to come into alinement with the exhaust ports 45 of the 70 cylinders and they extend around throughout substantially 180° as shown. On the inner side of the wall 47, the sides of the wheel are provided with inlet ports 50, and these ports are adapted to aline with the 75 inlet ports 44 of the cylinders, as shown. In the sides of the wheel, igniting pockets 51 are provided, and in these pockets 51, igniting coils 52 are placed, which are similar to the coils 38 in their construction and mode 80 of operation. The cylinders are all provided with spark plugs 53 which may be used for starting the engine or maintaining it in operation, acting as auxiliaries to the main sparking device 52. The direction of 85 rotation in this form of the invention is the same as in the preferred form, as indicated by the arrow in Fig. 5. The igniting device 52 is disposed slightly in the rear of the inlet port 50 with respect to the direction of 90 rotation. As indicated in Fig. 5, ignition is just beginning for the cylinder 43³. Soon after the port 50 passes out of communication with the port 44 of this cylinder, the ignition coil comes under the port 45 and ignition takes place. The cylinder does not 95 exhaust until it is just beginning its return stroke, at which time the forward end of the exhaust port 49 will come in communication with the port 45 of this cylinder as will be 100 readily understood. In this form of the invention it will be evident that an explosion takes place on every outward movement of each piston, although no compression of the charge takes place prior to ignition. 105

In the preferred form of the invention as illustrated in Fig. 1, the exhaust gases from the explosion cylinders pass into the outer portion of the case from which they find exit through a suitable exhaust pipe 54. 110

Having thus described my invention, I claim as new and desire to secure by Letters Patent,—

1. An engine having a shaft with skew cranks, a wheel mounted on said shaft between said cranks, cylinders disposed on opposite sides of said wheel and circumferentially arranged around said shaft, the axes of said cylinders being substantially parallel with the axis of said shaft, rockers carried by said skew cranks for rotating the same, pistons reciprocating in said cylinders, and rods connecting said pistons with said rockers. 115

2. An engine having a shaft with skew cranks, a wheel mounted on said shaft between said cranks, cylinders disposed on opposite sides of said wheel and circumferentially arranged around said shaft, the axes of said cylinders being substantially parallel 120

125

with the axis of said shaft, rockers carried by said skew cranks for rotating the same, pistons reciprocating in said cylinders, and rods connecting said pistons with said rockers, said wheel having ports affording means for controlling the admission to said cylinders.

3. An engine having a case, a shaft passing through said case and having skew cranks on opposite sides of said case, a plurality of cylinders attached to the sides of said case and circumferentially arranged about said shaft, the axes of said cylinders being substantially parallel with the axis of said shaft, rockers attached to said cranks and adapted to rotate said shaft, pistons reciprocating in said cylinders, rods connecting said pistons with said rockers, and a wheel within said case mounted on said shaft.

4. An engine having a case, a shaft passing through said case and having skew cranks on opposite sides of said case, a plurality of cylinders attached to the sides of said case and circumferentially arranged about said shaft, the axes of said cylinders being substantially parallel with the axis of said shaft, rockers attached to said cranks and adapted to rotate said shaft, pistons reciprocating in said cylinders, rods connecting said pistons with said rockers, and a wheel within said case mounted on said shaft, said wheel having ports affording means for controlling the admission and exhaust from said cylinders.

5. An engine having a shaft, a plurality of cylinders circumferentially arranged around said shaft and having their axes substantially parallel with the said shaft, a wheel mounted on said shaft between said cylinders and controlling the admission and exhaust therefrom, and means for rotating said shaft from said cylinders.

6. An engine having a shaft, a wheel mounted on said shaft and rotating therewith, a plurality of cylinders disposed in pairs on opposite sides of said wheel, said wheel having a receiving chamber for the gas and having admission ports leading from said receiving chamber to said cylinders, said wheel further having exhaust ports therein adapted to lead the gases of combustion from said cylinders, pistons reciprocating in said cylinders, the pistons in opposite cylinders moving in opposite directions with respect to each other, and mechanism connecting said pistons with said shaft for rotating the same.

7. A case, a shaft passing through said case, a plurality of cylinders attached to said case and circumferentially disposed around said shaft, said cylinders having their axes disposed substantially parallel with the axis of said shaft and being disposed in opposite pairs, pistons reciprocating

ing in said cylinders, mechanism connecting said pistons with said shaft for rotating said shaft, and a wheel mounted on said shaft and rotating within said case, the sides of the said wheel abutting against the walls of said case, means for admitting a gaseous fuel to said wheel, said case and said wheel having ports controlling the admission of charges of said fuel and exhaust from said cylinders, and means for exploding the charges in said cylinders.

8. An engine having a shaft with a skew crank, a plurality of explosion cylinders arranged circumferentially around said shaft and having their axes substantially parallel with said shaft, pistons reciprocating in said cylinders, a rocker on said skew crank, rods connecting said pistons with said rocker for rotating said shaft, a plurality of compressor cylinders disposed intermediate of said first cylinders, pistons reciprocating in said compressor cylinders to compress charges therein, means for driving said pistons from said rocker, means for controlling the admission of charges to said compressor cylinders, means for directing said compressed charges from said compressor cylinders into said explosion cylinders, and means for exploding the charges in said explosion cylinders.

9. An engine having a shaft, a plurality of circumferentially disposed explosion cylinders arranged around said shaft, a plurality of compressor cylinders also arranged around said shaft, pistons reciprocating in said explosion cylinders, means for rotating said shaft from said pistons, compressor pistons mounted in said compressor cylinders, means for actuating the same from said shaft, a wheel rotating with said shaft and having a compressing chamber which may communicate with said compressor cylinders, said compressing chamber having ports adapted to admit to said explosion cylinders, and means for exploding the charges in said explosion cylinders.

10. An engine having a shaft, a plurality of circumferentially disposed explosion cylinders arranged around said shaft, a plurality of compressor cylinders also arranged around said shaft, pistons reciprocating in said explosion cylinders, means for rotating said shaft from said pistons, compressor pistons mounted in said compressor cylinders, means for actuating the same from said shaft, a wheel rotating with said shaft and having a compressing chamber which may communicate with said compressor cylinders, said compressing chamber having ports adapted to admit to said explosion cylinders, and means for exploding the charges in said explosion cylinders, said wheel affording means for controlling the admission of the charges to said compressor cylinders.

11. An engine having a shaft, a plurality

of explosion cylinders disposed circumferentially around said shaft, pistons reciprocating in said cylinders, means connecting said pistons with said shaft for rotating the same, a plurality of compressor cylinders disposed circumferentially around said shaft, a wheel mounted on said shaft and having a receiving chamber for a gaseous fuel, said receiving chamber having ports which may admit to said compressor cylinders, pistons reciprocating in said compressor cylinders and actuated from said shaft, said wheel having a compressing chamber which may communicate with said compressor cylinders to receive a compressed charge therefrom, said compressing chamber having a port which may communicate with said explosion cylinders to admit a compressed charge thereto, and means for exploding the charges in said explosion cylinders.

12. An engine having a shaft, a plurality of explosion cylinders disposed circumferentially around said shaft, pistons reciprocating in said cylinders, means connecting said pistons with said shaft for rotating the same, a plurality of compressor cylinders disposed circumferentially around said shaft, a wheel mounted on said shaft and having a receiving chamber for a gaseous fuel, said receiving chamber having ports which may admit to said compressor cylinders, pistons reciprocating in said compressor cylinders and actuated from said shaft, said wheel having a compressing chamber which may communicate with said compressor cylinders to receive a compressed charge therefrom, said compressing chamber having a port which may communicate with said explosion cylinders to admit a compressed charge thereto, and means for exploding the charges in said explosion cylinders.

13. An engine having a shaft, a case through which said shaft passes, a plurality of explosion cylinders mounted on opposite sides of said case, circumferentially arranged about said shaft and having their axes disposed substantially parallel with said shaft, pistons reciprocating in said cylinders, means for rotating said shaft through said pistons, a plurality of compressor cylinders mounted on said case disposed circumferentially around said shaft, compressor pistons reciprocating in said compressor cylinders, means for reciprocating said compressor pistons, a wheel mounted on said shaft and rotating within said case, said wheel having a receiving chamber for a gaseous fuel, said receiving chamber having ports adapted to

admit fuel to said compressor cylinders, means for directing the compressed charges from said compressor cylinders into said explosion cylinders, and means for exploding the charges in said explosion cylinders.

14. An engine having a shaft, a case through which said shaft passes, a plurality of explosion cylinders attached to said shaft and circumferentially disposed around said shaft, said cylinders having their axes disposed substantially parallel with said shaft, pistons reciprocating in said explosion cylinders, means for rotating said shaft from said pistons, a plurality of compressor cylinders mounted on said case and disposed circumferentially around said shaft, compressor pistons reciprocating in said compressor cylinders, means for actuating said compressor pistons, a wheel mounted on said shaft and rotating within said case, said wheel having a receiving chamber for a gaseous fuel, said receiving chamber having ports adapted to admit charges to said compressor cylinders, said wheel further having a compressing chamber having ports adapted to communicate with said compressor cylinders to receive a compressed charge therefrom, said compressor chamber further having ports adapted to communicate with said explosion cylinders to admit the compressed charge thereto, said wheel further having ports controlling the exhaust from said explosion cylinders, and means for exploding the charges in said explosion cylinders.

15. An engine having a shaft, a plurality of cylinders arranged circumferentially, means for driving said shaft from said cylinders, a wheel affording means for admitting explosive charges to said cylinders, and an igniting device carried by said wheel and passing said cylinders successively to explode said charges.

16. An engine having a shaft, a case, a wheel carried by said shaft and rotating in said case, a plurality of cylinders attached to said case and having their axes disposed substantially parallel with said shaft, said cylinders being arranged circumferentially about said shaft, said wheel affording means for admitting explosive charges to said cylinders, an igniting device carried by said wheel and adapted to explode said charges, and means for rotating said shaft from said cylinders.

In testimony whereof I have signed my name to this specification in the presence of two subscribing witnesses.

CARL BECKMANN.
